METHOD AND APPARATUS FOR HEAT TREATING METAL ARTICLES

Filed Oct. 27, 1924

FIG. 1.

Inventor

Thomas F. Callaghan
Thurston Knob T. Hudson

Attorney S.

UNITED STATES PATENT OFFICE.

THOMAS F. CALLAGHAN, OF BELLEFONTE, PENNSYLVANIA, ASSIGNOR TO ERWIN C. UIHLEIN, OF MILWAUKEE, WISCONSIN.

METHOD AND APPARATUS FOR HEAT TREATING METAL ARTICLES.

Application filed October 27, 1924. Serial No. 746,094.

The present invention relates to a method and apparatus which is particularly designed for the heat treatment of metal articles.

One of the objects of the invention is to 5 perform the heat treating of metal articles by enclosing the articles to be heated in an enclosure under such conditions that the oxidation of the articles during the heat treating process and subsequent thereto will 10 be substantially eliminated, or at least held to a minimum amount.

A further object of the invention is to provide a method and construction by which the articles are quenched while maintained 15 in such condition that they are free from influences of oxygen or oxidizing actions.

Other objects of the invention will appear as the description proceeds.

Reference should be had to the accompanying drawings, in which Fig. 1 is an elevation of an apparatus embodying the present invention, and in which the method herein described may be performed. Fig. 2 is a section upon the line 2—2 of Fig. 1.

20 It may be generally stated that the method and the apparatus for accomplishing the method which are herein described are for the purpose of heat treating metal articles so that while they are being heat treated 25 they will be maintained under conditions which will exclude air or other oxidizing influence, and subsequent to the heating operation the articles may be plunged in a quenching bath while still maintained out of contact with air.

This method is of particular importance 30 in connection with certain classes of dies, tools, and other articles of similar nature in which the dies or tools are brought to their proper final shape while the metal is soft, and it is very desirable that when they are hardened they shall not be covered with an undue amount of scale, which always is the consequence when these articles are heat 35 treated by usual methods, or where they are case-hardened. All these methods of heat treating which have been mentioned invariably produce a more or less heavy scale which requires considerable refinishing and 40 additional work upon such articles after they have been heat treated or case-hardened.

It may be stated that the method of heat 45 treating which is herein proposed consists in confining the articles to be heat treated 50 within a suitable enclosure from which en-

closure, at the time of the heating, the air is removed. This does not mean necessarily that there is a perfect vacuum formed, but it is entirely feasible by the use of commercial exhaust pumps which are now 60 known, to remove at least the major portion of the air from such a container so that the oxidizing action which could take place during the heat treating action would be almost negligible, or at least, it would be 65 so small as to require a minimum amount of additional work in refinishing the article after the heat treating process.

The second step in the method which is herein proposed consists in quenching the 70 articles which have been heat treated in a suitable quenching bath while still maintaining the condition of vacuum or partial vacuum so as to protect the articles against oxidation until they are immersed in the 75 quenching bath. After the quenching operation the temperature of the articles is sufficiently reduced so that the danger of oxidizing action thereafter is removed.

In the present invention one form of apparatus for carrying out the method is shown, although no limitation is intended with respect to the process by the disclosure and description of the following apparatus.

In the drawings, 1 indicates an enclosure 80 which may be cylindrical, rectangular, elliptical, or any desired shape, and comprises a bottom wall and side walls which are integral and nonporous. This enclosure may be formed of metal. At the upper end of the 85 body 1 there is an outwardly extending annular flange 2 and this co-operates with a flange 3 formed on a dome-shaped cover member 4. It will doubtless be desirable to insert a packing ring, such as metal, between the flanges 2 and 3 in order to secure a hermetically tight joint. The cover member 4 may be held onto the body 1 by any suitable fastening means, as by means of the nut and bolt structure which is indicated at 90 95 100 5 in the drawings.

Within the container 1 there is a metal shell 6 which in the present instance is shown as annular, and is cylindrical in shape, although the particular shape of the same is not important. This shell upon the inside has attached thereto a layer of heat resisting and electrically insulating material, such as indicated at 7. The shell 6 and the lining 7 may be supported upon plates, one of 110

which is shown at 8, which plate is in turn supported by an angle bracket 9, these plates and angle irons being distributed at suitable intervals beneath the shell 6 in order to support it.

Upon the wall of insulating material 7 there will be carried, in any suitable fashion, resistance material, such as indicated at 10, which will develop the required heat when a 10 suitable electric current is passed through the resistance.

Upon the inside of the cover 4 there is a cap member which is generally designated at 11. This cap member has an outer portion which may be of metal, and an inner portion 12 which may be of heat resisting material, the heat resisting material forming an inner lining.

The member 11 is supported from the 20 cover 4 by means of links 13 or any other suitable manner, and the arrangement is such that the member 11 will be freely resting upon the upper end of the shell 6 and the body of resisting material 7 when the 25 cover 4 is in its proper position with respect to the enclosing member 1.

Extending through the member 1 and the cover 4 is a support which is generally indicated at 14. This support comprises a hollow 30 tubular portion 15 which extends upwardly through the member 11 and the cover 4, and which is suitably packed at the portion where it extends through the cover 4, as indicated at 16, and it also includes right 35 angled extending portions 17 which may be four, as shown in the drawing, or any other suitable number. Within the tubular portion 15 there is an inner pipe 18 which at its lower end has right angularly extending 40 pipes 19, each of the pipes 19 extending into one of the extensions 17. At the upper end of the tubular member 15 there is an outlet pipe 20, and communicating with the inner pipe 18 there is an inlet pipe 21. Water 45 may be circulated through the pipe 21. The pipe 18 and the branch pipes 19, and the return, will be through the extension 17, the tubular member 15, and the exit pipe 20. Thus there will be maintained a circulation 50 of cooling water which will be sufficient to prevent melting or ill effects due to the heat within the chamber.

The plates 8 have pivotally connected thereto two swinging door members 22 and 55 23, these door members cooperating by means of an overlay, as indicated at 24. These gate members 22, 23, are mounted upon rods, one of which is indicated at 25, which extend upon the outside of the enclosure member 1, and there may be operated by suitable means to open or close the same, as may be desired.

In the lower portion of the enclosure member 1 there will be confined a body of 60 quenching liquid, as indicated at 26. This

liquid may be introduced or taken out by means of the valved pipe 27.

In order to agitate the quenching medium, a stirring blade 28 is provided, the shaft of which extends upon the outside of the member 1, and may be suitably rotated.

Within the lower portion of the member 1 there extends a coil of pipe, such as indicated at 29, through which a cooling medium may be circulated in order to maintain the temperature of the quenching medium to that which may be desired.

Adjacent the upper end of the enclosing body 1 there is a pipe 30 which is adapted to be connected with a suitable exhausting 80 pump or other apparatus, by which air may be exhausted from the interior of the enclosing member 1. No particular apparatus need be shown as apparatus which will accomplish this function is well known in the 85 art.

The articles which are to be heat treated are carried by the extensions 17, these forming a support for such articles in approximately the middle portion of the heating 90 zone of the apparatus.

When articles to be heat treated are suitably supported upon the extension 17 and the cover 4 is brought into closed position, as shown in the drawing, the air may be exhausted through the exhaust pipe 30, and the electric current caused to pass through the resistance elements 19. The heat which will thus be generated will be reflected from the walls toward the center of the furnace, and 100 also from the top of the furnace, thus enabling an exceedingly high temperature for heat treating purpose to be obtained.

Due to the fact that the air is exhausted from the chamber in which the heat treating 105 is being effected, there can be no oxidizing action except to the very limited extent permitted by the presence of such air as is not exhausted. But this, as will be clearly seen, is a function of the degree of exhaustion 110 which is obtained and may be controlled. When the heating of the metal articles is completed, the closure members 22 and 23 are opened and the supports 17 with the tubular member 15 are lowered into the 115 quenching bath, which as will be clearly seen, is also under sub-atmospheric conditions, so that the non-oxidizing conditions are maintained during the quenching operation.

As soon as the quenching is completed the 120 cover 4 may be removed and with it the tubular member 15 and the support 17 and the articles which have been heat treated.

It will readily be appreciated that in the practice of the method which has been described, that if it be desired, carbonizing gases may be introduced into the furnace or the container, as it has heretofore been called, so that the metal articles being heat treated may be subject to the action of the carboniz- 130

ing gases at the same time they are heated.

It is also within the province of the present invention to supply an atmosphere of an inert gas after the air has been exhausted therefrom. Such inert gases will be free from any oxygen or oxidizing element, so that no oxidation of metal articles within the furnace will be effected.

Having described my invention, I claim:—

1. In an apparatus of the character described, the combination with a container, a closure member for said container, a shell within the container which is spaced from the wall of the container, and means for supporting said shell, a refractory lining upon the inner wall of the shell, electric resistance members carried by the said refractory wall, a cap co-operating with the said shell and refractory lining upon the inner wall of said cap, means through which air may be exhausted from the interior of the container, a movable supporting means within the said container for supporting articles to be heat treated, a quenching bath compartment within said container the said movable supporting means being adapted to move into said quenching bath compartment.

2. In apparatus of the character described, the combination of a container, one portion of said container serving as a quenching bath compartment, another portion of said container having a shell within the same, said shell being spaced from the wall of the container, means for supporting said shell within the container, a suitable refractory lining upon the inner wall of said shell, electric resistance members within the shell, a cap co-operating with said shell said cap having a suitable refractory lining, a movable member for supporting articles to be heat treated, said movable member having portions which extend through the said cap and said closure member for the container said movable member being adapted to move into the quenching compartment.

3. In apparatus of the character described, the combination with a container having at

the lower portion thereof a compartment adapted to contain a quenching medium, closure members above said compartment, a shell within said container and spaced from the wall thereof above the said quenching compartment, a refractory lining upon the interior of said shell, electrical resistance elements within said shell, a cap co-operating with the said shell at the upper end thereof said cap having a refractory lining upon the inner wall thereof, a closure member for the said container, a conduit through which air may be exhausted from the container, movable means for supporting articles to be heat treated, said movable means being capable of being moved from the heat compartment to the quenching compartment.

4. In apparatus of the character described, the combination in a container, a portion of said container being adapted to contain a quenching medium, cooling means associated with the container for maintaining the quenching media at desired temperature conditions, agitating means associated with said compartment of the container for agitating the quenching media, a shell supported within said container above the quenching compartment said shell being spaced from the wall of the container, means for supporting the shell, a lining of refractory material upon the inner wall of the shell, a cap member co-operating with the upper end of said shell said cap member having a refractory lining upon the inner surface thereof, a closure member for said container, a conduit communicating with the interior of the container by which air may be exhausted therefrom, a movable supporting member having portions extending through the cap and the closure for the container said member being adapted to support articles to be heat treated, said member being movable from the heat treating compartment to the quenching compartment.

In testimony whereof, I hereunto affix my signature.

THOMAS F. CALLAGHAN.
